Primary Examiner — Cathron C Brooks*Assistant Examiner* — Deanna Fluegeman(74) *Attorney, Agent, or Firm* — Knobbe Martens Olson & Bear LLP(57) **CLAIM**

The ornamental design for a portion of a display screen with a user interface, as shown and described.

DESCRIPTION

The FIGURE is a front view of a portion of a display screen with a user interface showing the claimed design.

The portions of the user interface illustrated in broken lines form no part of the claimed design. The portion of the display screen is understood to be congruent with the shape of the user interface.
